UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

SOUND-REPRODUCING APPARATUS.

Application filed October 28, 1925. Serial No. 65,472.

My present invention relates to apparatus for the reproduction of sound, and more particularly to systems in which electric currents produced from sound records are amplified by means of thermionic amplifiers and employed for sound reproduction.

In cases where electric currents are produced from a sound record, such, for example, as an ordinary phonograph record and amplified to operate a sound reproducing device, it is desirable to provide means other than the awkward and unsatisfactory method of changing the stylus or needle for regulating the sound produced.

15 The preferable means for accomplishing this is to control the voltage supplied to the input of the amplifier. In some cases this may be accomplished by means of a variable ratio transformer, which may be an auto-transformer, between the pick-up device by which the electric currents are produced and the input circuit of the amplifier. Situations sometimes arise, however, where a resistance potentiometer control is preferable 20 to the use of a variable ratio transformer. The resistance potentiometer can in general be more cheaply constructed than the transformer, and if properly designed it introduces less distortion of the audio frequency current than does a transformer. 25 Transformers give rise to distortion because of distributed capacity in their windings, and because they take a magnetizing current whose wave form differs from that of the impressed voltage. If several transformers are already in use in the amplifying system, it is especially desirable to avoid introducing an additional transformer since the distortion from the several transformers is 30 cumulative. My invention relates to the control of the voltage supplied to an amplifier particularly when it is desired to supply the input voltage to the primary winding of a transformer already incorporated in the 35 amplifier for some other purpose, for example, when the same amplifier serves for both radio reception and reproduction from phonograph records.

The object of my invention is to provide 40 a means for controlling the intensity of the sound produced by such a system in such a way as to avoid distortion. A more specific object of my invention is to provide an apparatus in which all frequencies will be reproduced in substantially their original

relative values irrespective of the setting of the intensity control apparatus.

The novel features which I believe to be characteristic of my invention are set forth with particularity in the appended claims; 60 my invention itself, however, will best be understood by reference to the following description taken in connection with the accompanying drawing in which I have illustrated diagrammatically an apparatus 65 which may be used in carrying my invention into effect.

I have indicated in the drawing an amplifying tube 1 to the input circuit of which audio frequency current is supplied by 70 means of an input transformer 2. The output circuit of the device includes the primary winding 3 of a transformer 4. The secondary winding 5 of this transformer is arranged to supply current to the actuating 75 coil 6 of a reproducing device. This coil may be employed to actuate a diaphragm 7, which may be of any desired type. The currents supplied to the input circuit of the amplifier may be produced by a pick-up 80 device comprising an armature 8, which is adapted to be vibrated by a stylus 9 operating in the groove of an ordinary phonograph record. The armature 8 may be arranged so that its vibrations vary the flux 85 through coil 10. The flux is produced by a magnet which is not indicated. I include in the circuit between coil 10 and the primary of transformer 2 a potentiometer comprising a resistance 11, which is shunted 90 across the coil 10. By means of a variable tap 12 the amount of this resistance which is included in shunt to the primary of the transformer 2 may be varied at will and thereby the voltage applied to the amplifier 95 and the intensity of the sound produced by the diaphragm 7 may be controlled as desired.

I have found that in a system such as shown and described, there must be certain 100 relations between the reactance of the magnetic pick-up, the reactance of the transformer primary and the resistance of the potentiometer, in order that distortion may be avoided.

One of these requirements is that the potentiometer must have a total resistance 105 which exceeds the maximum reactance of the pick-up at the frequencies to be reproduced. At the same time the minimum re- 110

actance of the transformer primary winding should exceed the maximum resistance which can be introduced into the transformer circuit by the potentiometer. When the potentiometer is set for maximum intensity, that is, with the tap 12 connected to the end of the resistance 11, so that the total resistance is included in shunt to the transformer primary it does not introduce any resistance in series with the transformer winding, but simply constitutes an extra load across the pick-up device. When, however, the potentiometer is set for 50 per cent of the maximum intensity, that is, with the tap 18 12 at the midpoint of resistance 11, it introduces a resistance in the transformer circuit equal to one-fourth of the total resistance of the potentiometer. This resistance consists of the two halves of the resistance 20 11 in multiple. Any other setting of the tap 12 will give a lower resistance in the transformer circuit.

To illustrate the manner in which the circuit should be proportioned, assume that 25 the transformer primary has an inductance of 30 henries and that it is desired to reproduce sounds covering a frequency range of 100 to 4000 cycles without appreciable distortion. The transformer reactance will be 30 a minimum of 100 cycles and will be equal to

$$6.28 \times 100 \times 30 = 18,800 \text{ ohms.}$$

This should preferably exceed a quarter of the resistance of the potentiometer, or in other words, the potentiometer resistance should be less than $4 \times 18,800$, or 75,000 ohms. If this condition is not complied with there will be an unduly large loss of low frequencies in their reproduction. With the value given, current at 100 cycles would suffer a loss of about 30 per cent as compared with a 1000 cycle current but this loss is not ordinarily sufficient to injure the 45 acoustic reproduction. If the potentiometer resistance is made higher than the value given, the low frequencies will be reduced to a much greater extent. On the other hand, a lowering of the resistance makes only a slight reduction in the difference between the low and high frequencies.

If the potentiometer has a resistance of 55 75,000 ohms the pick-up coil must be made to have a maximum reactance which will not exceed 75,000 ohms. Since this reactance will be greatest at the highest frequency required, and 4000 has been assumed as the upper frequency limit, the inductance of the pick-up coil must not exceed

$$60 \quad \frac{75,000}{6.28 \times 4000},$$

or approximately 3 henries. If the inductance of the pick-up coil exceeds this value there will be a disproportionate loss of the

high frequency components. If the pick-up coil has a lower inductance or the transformer a higher inductance than required by the above relation there is a greater latitude in the choice of resistance for the 70 potentiometer and the range of frequency which can be covered without appreciable distortion is increased. For example, if the transformer inductance is 30 henries and the pick-up 1 henry, the potentiometer may have 75 any value of resistance desired between 25,000 and 75,000 ohms.

What I claim as new and desire to secure by Letters Patent of the United States, is:—

1. The combination in a sound reproducing apparatus of a thermionic amplifier adapted to amplify audio frequency currents, a pick-up device for producing electric currents from sound records, a transformer connected in the input circuit of said amplifier and arranged to be supplied with current from said pick-up device, and a potentiometer connected in a circuit between the primary of said transformer and said pick-up device, the total resistance of said 90 potentiometer being substantially as great as the maximum reactance of said pick-up device and the minimum reactance of the primary winding of said transformer being at least substantially as great as the maximum 95 resistance introduced in the circuit of the transformer by the potentiometer.

2. The combination in a sound reproducing apparatus of a thermionic amplifier adapted to amplify audio frequency currents, a pick-up device for producing electric currents from sound records, a transformer connected in the input circuit of said amplifier and arranged to be supplied with current from said pick-up device, a 100 resistance connected in shunt to said pick-up device, and means for including a variable portion of said resistance in shunt to the primary of said transformer, the value of said resistance being substantially as 105 great as the maximum reactance of said pick-up device, and the minimum reactance of said primary winding being at least substantially as great as the maximum 110 resistance which can be introduced in the circuit 115 of the transformer by said resistance.

3. The combination in a sound reproducing apparatus of a thermionic amplifier adapted to amplify audio frequency currents, a pick-up device adapted to produce electric 120 currents from sound records, a transformer connected in the input circuit of said amplifier and arranged to be supplied with current from said pick-up device, a resistance connected in shunt to said pick-up 125 device and means for including a variable portion of said resistance in shunt to the primary of said transformer, the value of said resistance being substantially as great as the maximum reactance of said pick-up 130

device but not appreciably greater than four times the minimum reactance of the primary of said transformer at the frequencies to be reproduced.

- 5 4. The combination in a sound reproducing apparatus of a thermionic amplifier adapted to amplify audio frequency currents, a pick-up device adapted to produce electric currents from sound records, a transformer connected to the input circuit of said amplifier and arranged to be supplied with current from said pick-up device and a potentiometer connected in a circuit between the primary of said transformer and said pick-up device, the total resistance of said potentiometer being substantially as great as the reactance of said pick-up device at the highest important frequency to be amplified and the reactance of said primary winding of the transformer at the lowest important frequency to be amplified being at least substantially as great as the maximum resistance introduced in the circuit of the transformer by the potentiometer.

5. The combination in a sound reproducing apparatus of a thermionic amplifier adapted to amplify audio frequency currents, a pick-up device adapted to produce electric currents from sound records, a transformer connected in the input circuit of said amplifier and arranged to be supplied with current from said pick-up device and a potentiometer connected in a circuit between the primary of said transformer and said pick-up device, the total resistance of said potentiometer being substantially as great as the reactance of said pick-up device at a frequency of about 4,000 cycles and the reactance of the primary winding of said transformer at a frequency of about 100 cycles being at least substantially as great as the maximum resistance introduced in the circuit of the transformer by a potentiometer.

In witness whereof, I have hereunto set my hand this 27th day of October, 1925.

EDWARD W. KELLOGG.
